(57) **CLAIM**

The ornamental design for a pistol recoil simulator, as shown and described.

DESCRIPTION

FIG. 1 is a rear perspective view of a pistol recoil simulator according to my novel design;

FIG. 2 is a typical side elevation view, thereof, the pistol recoil simulator being symmetrical about a longitudinal axis;

FIG. 3 is a rear elevation view, thereof;

FIG. 4 is a front elevation view, thereof; and,

FIG. 5 is a reduced scale, fragmentary front perspective view, showing the article in environment; the pistol shown in broken lines is included solely for illustrative purposes, forming no part of the claimed design.
